UNITED STATES PATENT OFFICE.

MINIFRED DAWES THOMAS, OF CHICAGO, ILLINOIS.

BED.

Application filed June 9, 1927. Serial No. 197,631.

This invention relates to folding or collapsible beds or more particularly to beds of this character which are adapted to be folded or collapsed by moving the head and foot portions of the bed toward each other by parallel or straight-line movement.

The principal object of this invention is to provide a bed which may be adjusted so that it will require but comparatively little floor space so that it is particularly adapted for use in apartments or in rooms where the floor space is limited or is to be used for other purposes than sleeping rooms. Other objects of this invention are to provide an improved folding or collapsible bed which will be convenient in operation and attractive in appearance; to provide a bed having a folding mattress and means for automatically folding the mattress when the bed is moved to folded or retracted position; to provide a bed having head and foot portions with folding rails of the lazy tongs type which are arranged to hold the head and feet in parallel relation while permitting their being moved toward and away from each other; to provide a bed having folding rails and a folding mattress with means for swinging the mattress to vertical folded position; to provide a bedstead having a folding bed bottom with a mattress or the like associated therewith and adapted to be moved from an extended horizontal to a folded vertical position; and to provide such other advantages and improvements as will appear hereinafter.

In the accompanying drawings illustrating a preferred form of my invention,

Figure 1 is a side view with parts broken away to show the inner construction;

Figure 2 is a plan view also with portions broken away;

Figure 3 is a side view showing the bed in folded or collapsed position;

Figure 4 is a cross sectional view taken on the line 4-4 of Figure 3;

Figure 5 is an enlarged sectional detail; and

Figure 6 is a plan of the parts shown in Figure 5.

My improved bed comprises a head portion 7 and foot portion 8 which may be formed in any suitable manner but which are preferably curved inwardly, as shown in detail in Figure 6 to connect with posts 9 and 10. Instead of the usual side rails, I provide extensible or adjustable devices for

supporting the bed or bed bottom while at the same time permitting the foot and head or end portions of the bed to be moved toward and away from each other so that when the bed is not in use, it may be shortened to occupy as small an amount of space as possible. In the arrangement shown, these extensible devices comprise lazy tongs 11, the end levers of which are pivoted respectively to the head and foot, as shown at 12 and 13. The coacting end levers of the lazy tongs are provided at the head and foot respectively with pins or projections 14 and 15 which engage with slots 16 and 17 in plates of guideways 18 and 19, secured to the head and foot posts. The pins are preferably provided with heads, as shown in Figure 6, which are adapted to move longitudinally in the guideways and prevent the pins from becoming disengaged from the slots. When the bed is in normal or extended position, as shown in Figure 1, the pins will engage with the upper ends of the slots in order to prevent further longitudinal or opening movement of the bed and the parts will be in locked position so that these side members or lazy tongs will support the mattress or other portions of the bed proper. When the bed is folded or collapsed, as shown in Figure 3, the pins will be at the bottom ends of the slots and the levers forming the lazy tongs will be moved to closed or folded position. This will ordinarily be accomplished by pushing the foot of the bed toward the head until the parts reach their extreme closed positions, at which time the bed will occupy a comparatively small amount of space. While it is not the intention to disguise the bed, the parts may, if desired, be constructed or designed so that the bed when folded may have the appearance of some other piece of furniture.

The lazy tongs or side members 11 are provided with transverse supporting members such as the slats or bars 20, as shown particularly in Figures 5 and 6, for supporting the mattress or bed 21. These slats are each preferably provided with two engaging faces or surfaces 22 and 23 which are arranged at an angle to each other, one face being horizontal when the bed is in open position and the other face being horizontal when the bed is in closed position, thereby forming substantial engaging surfaces for supporting the mattress in both positions. The mattress 21 is preferably divided into

two parts and provided with a hinge adjacent to the upper surface, as shown at 24, so that the parts may be folded together. The division of the parts is preferably nearer the foot of the bed than the head so that the hinge or line of division will come approximately under the knees of the person lying on the bed, and therefore will not be likely to be noticed. Furthermore, by 10 having the divisions of unequal length, a space is provided when the bed is closed, as shown in Figure 3, for the pillows 25.

In order to raise the ends of the mattress to vertical folded position, I provide oppositely disposed pairs of arms 26 and 27 at the head and foot of the bed, respectively, which arms are formed with or rigidly secured to some of the levers of the lazy tongs whereby their outer ends will be swung upwardly as the lazy tongs are contracted or folded together. Cross pieces or rollers 28 and 29 are carried at the outer ends of the pairs of arms and adapted to roll or move along the lower surface of the mattress as 15 the ends are being swung upwardly. These parts are so constructed that as the foot is pressed toward the head, these arms will cause the ends of the mattress to be raised or swung on their hinge, and as the closing 20 movement is continued, the ends of the mattress will engage with the head and foot so as to slide upwardly to the final closing position, as shown in Figure 3. If desired cross pieces or rollers such as shown at 28 and 29 may be used in the place of the transverse supporting members 20. The parts 25 are preferably so proportioned that when the bed is closed the space between the head and foot will only be sufficient to accommodate the mattress and other bedding. The bed clothes, such as the sheets and 30 blankets may be fastened to the mattress by means of straps 30, having suitable buttons or fasteners 31 so that such clothes will be 35 swung or folded with the corresponding portions of the mattress.

It will be noted that the space between the ends of the mattress and the head and foot boards is preferably such as to permit a 40 sufficient movement of the lazy tongs to raise the ends of the mattress a short distance before they are engaged by the head and foot, this being in order to facilitate the closing operation.

From this description, it will be seen that I provide a bed which can be made in any 45 desired size but which when extended will be substantially the same as an ordinary bed, and which when folded will occupy but little room. Furthermore, my improved bed 50 cannot be inadvertently swung or moved to closed position, such as may occur in some types of ordinary folding beds, and therefore avoids the dangerous features of such 55 beds.

It will, of course, be apparent that changes may be made in the construction and in the arrangement of the parts or details of my improved bedstead in order to adapt it for different conditions or to 70 make different designs thereof; therefore, I do not wish to be limited to the exact arrangement herein shown and described, except as specified in the following claims, in 75 which I claim:

1. The combination with the head and foot of a bed, of side members comprising lazy tongs, means for connecting the lazy tongs with the head and foot to permit the head and foot to be moved toward and away 80 from each other, a series of transverse slats carried by said side members, a hinged mattress adapted to be supported in horizontal position by said slats and means operatively connected to the side members for raising 85 the ends of the mattress when the head and foot are moved toward each other.

2. A bed comprising end members, lazy 90 tong side members connecting the end members, transverse mattress supporting members carried by said lazy tongs, a mattress formed in two parts and hinged together and means operatively connected to the 95 lazy tongs for raising the ends of the mattress when the bed is closed.

3. The combination with lazy tong side rails for a bed, of transverse slats connected to the upper jointed ends of the lazy tong levers and having engaging faces for supporting a mattress, said faces being arranged at an angle to each other so that one face will be in horizontal position when the bed is closed, and the other face will be in 100 horizontal position when the bed is open.

4. In a bed construction, the combination 105 of end members having curved portions connecting with the posts, guideways secured to the posts, lazy tong side rails having their upper extremities pivoted to the posts and their lower extremities provided with guides 110 engaging with said guide-ways, oppositely disposed pairs of curved arms secured to certain of the lazy tong levers adjacent to the ends thereof, rollers mounted between the ends of the pairs of arms, transverse 115 slats carried by said lazy tongs, and a mattress comprising two parts which are hinged together and adapted to be supported on said slats, the arrangement being such that the said rollers will move upwardly beyond the slats when the bed is closed and will tend to raise the ends of the mattress 120 upwardly.

5. The combination with collapsible side 125 rail members comprising pivoted levers of the character set forth, of transverse slats rigidly secured to the levers adjacent to their upper pivots, each slat having two engaging faces arranged at an angle to each other and adapted to engage with a mattress, one 130

of said faces being horizontal when the side rail members are collapsed and the other face horizontal when the side rail members are extended.

5 6. A bed construction comprising end members connected by lazy tong side rails, transverse slats rigidly connected to the upper portions of the lazy tong members and having engaging faces for supporting 10 a mattress, said faces being arranged at an angle to each other so that one face will be in horizontal position when the bed is closed, and the other face will be in horizontal position when the bed is open, oppositely disposed pairs of arms secured to certain 15 of the lazy tong levers adjacent to the ends thereof, and means carried by said arms for engagement with the ends of a folding mat-

tress and adapted to raise the ends of the mattress away from the slats when the bed 20 starts to be closed.

7. The combination with the head and foot of a bed, of lazy tong side members, means for connecting the side members with the head and foot to permit them to be 25 moved toward and away from each other, a series of transverse supporting members carried by said side members and adapted to support a hinged mattress, arms secured to the side members adjacent to the ends 30 thereof and adapted to swing upwardly as the side members collapse, and cross pieces carried by said arms and adapted to engage with and raise the ends of the mattress when the bed is being closed.

MINIFRED DAWES THOMAS.
